UNITED STATES PATENT OFFICE.

HUGO F. BIEDERMANN, OF TUSCALOOSA, ALABAMA.

SAWMILL-CARRIAGE SETWORKS.

Application filed May 10, 1924. Serial No. 712,446.

To all whom it may concern:

Be it known that I, HUGO F. BIEDERMANN, a citizen of the United States, residing at Tuscaloosa, in the county of Tuscaloosa and State of Alabama, have invented certain new and useful Improvements in Sawmill-Carriage Setworks, of which the following is a specification.

This invention relates to a sawmill carriage set works, and particularly to a construction adapted to effect a tensioning or snubbing action between the set shaft and the knee and the individual adjusting means for the knee in order to eliminate all slack and lost motion between these parts.

In this art it is important in securing straight or accurate sawing to avoid any slack between the setting parts which would result in displacement of the knee in the operation of the saw, and such slack or lost motion is commonly due to loose connections and wear of movable members which defeat a firm and accurate adjustment of the knees both from the set shaft and for the individual adjusting lever therefor. The lost motion due to this slack rapidly increases in the use of the set works, due to friction, and frequently becomes such an element as to permit a definite movement of the knee in the cutting action of the saw upon the timber, which defeats a straight cut and also the object of the individual adjusting lever by which a finer adjustment of the knees independently of the set shaft is effected.

For the purpose of obviating these objections in the practical operation of a sawmill set works I have provided a flexible connection extending from the setting shaft to the adjusting lever for the knee, with means for maintaining this connection under a constant and even tension as it is fed from the set shaft during the movement of the knee in the successive cutting operations. Such a connection effectually retains the adjusting lever and its latch in close contact while all of the slack between the setting rack and its pinion is taken up so that the parts when adjusted are firmly and accurately held.

The invention has for an object to provide a novel and improved construction of sawmill set works in which a flexible connection extends from the set shaft on the carriage to the individual adjusting lever for the

knee, together with means for maintaining said connection under a constant tension.

A further object of the invention is to provide an improved construction of the tensioning means adapted to be mounted upon the head block and comprising a cylinder having a piston projected therefrom and carrying a sheave over which the flexible connection between the parts is extended.

Another object of the invention is to provide an improved construction of cuff adapted for adjustable mounting upon the adjusting lever so as to maintain the latch member in intimate contact with the lever and through the cooperation of the tension device with said lever in constant contact with one of the engaging walls of the sector with which the latch cooperates.

Other objects and advantages of the invention will be hereinafter set forth and the novel features thereof defined by the appended claims.

In the drawings:—

Figure 1 is an elevation of the head block and knee setting mechanism with parts broken away and in section;

Figure 2 is a longitudinal section through the tensioning device;

Figure 3 is a top plan thereof showing the connection with the setting shaft;

Figure 4 is an elevation of the attaching cuff with the upper portion in section;

Figure 5 is a section on the line 5—5 of Figure 4; and

Figure 6 is a similar view on the line 6—6 of Figure 4.

Like numerals refer to like parts throughout the several figures of the drawings.

The invention may be applied to any desired type of sawmill carriage or head block and in its present application the carriage 10 is provided with a head block 11 which carries a setting shaft 12 provided with the usual pinion 13 which cooperates with the rack teeth 14 of the sliding rack 15 by which the knee 16 is adjusted. The adjustment of all of the knees is simultaneously effected through this connection in the usual manner.

The present invention provides for an independent adjustment of each knee relative to the rack so as to effect an individual action thereof in properly aligning the timber to be cut. This is necessary where

inclined faces are encountered as it is often desirable to set one knee at a different position from the others, particularly in removing the outer slab or layer from a log and in compensating for a previously irregularly sawed surface. This individual adjustment is effected by means of a lever 17 pivotally mounted at 18 upon the rearward extension 19 of the knee and having its lower end connected by a link 20 to a fixed point 21 upon the rack 15. This rack being held in its set position permits an independent sliding adjustment of the knee thereon through the connection described.

The tensioning device with which the present invention is primarily concerned consists of a flexible connection 22 of any desired character, such as the chain which extends from a drum 23 upon the set shaft 12 to a tension lever 24 mounted upon the same pivotal axis 18 as the adjusting lever 17. The lower end 25 of this lever is provided with a series of connecting apertures 26 by which the end portion 27 of the flexible connection may be adjusted upon the tension lever when the parts are assembled.

The winding drum 23 upon the shaft 12 may be of any preferred character and is herein shown as provided with spiral ways by which overlapping of the chain layers is prevented and an even feed secured therefrom.

The tension device applied to the flexible connection 22 may be of any preferred character, a desirable form being herein shown as comprising a cylinder 28 having a piston member 29 at the outer end of which a wheel or sheave 30 is pivotally mounted at 31 and over which the connection 22 passes. For maintaining a proper tension a coiled spring 32 is disposed within the cylinder and bears against the piston member and also the head 33 applied to the cylinder. For the purpose of adjusting this tension and limiting the movement in the expansion of the spring, a threaded shank 34 extends from the piston through said spring and head where an adjusting nut 35 is applied. While a spring member has been shown for providing the tension, it will be obvious that fluid pressure could be used for the same purpose.

For the purpose of attaching the tension lever 24 to the adjusting lever 17 a post 36 is extended from the lever 17 and forms a pivotal connection for the upper end of the tension lever 24. The adjusting lever is surrounded by a cuff 37 which encloses the same and also the latch member 38 which cooperates with the notched or toothed sector 39. This cuff carries at the opposite side from the latch a block 40 in which set screws 41 are threaded so that when properly adjusted the latch is drawn into firm contact with the face of the adjusting lever and also

through the tension connection before described held in contact with a wall of the sector seats. For the purpose of permitting such adjustment the cuff is provided with slots 42 and a retaining bolt 43 from the lever 17 is disposed therein to properly align the parts in their adjustment in connection with the bolt 36.

In the operation of the invention it will be seen that the flexible tension connection between the adjusting lever and the setting shaft provides means for taking up all slack or lost motion both between the rack and its pinion and also between the individual adjusting levers and their connections. When the parts are assembled the adjusting nut upon the shank of the piston member is threaded into contact with the head until the desired tension is established in the spring member and the flexible connection adjusted to a tight position upon the tension lever. This nut is then threaded off a sufficient distance to permit the proper play or length of travel of the piston and the cuff is properly set upon the adjusting lever to prevent any lost motion in the latch connection.

As the knee is successively advanced the flexible connection is unwound from the set shaft and passing over the sheave the parts are constantly maintained under an equal tension so that a yielding of the knee through pressure or other causes is practically prevented while the knee may be individually adjusted upon the rack through the adjusting lever to the desired extent to effect a true cut of the timber. It will be observed that the construction is such that in the advance of the knee a constant tension is maintained while in the reverse movement the chain slack is taken up by the setting shaft so that a preliminary setting of the parts at the proper tension is sufficient for their continued operation.

While the specific construction of the adjusting lever and the flexible connections have been shown and described, still the invention is not confined thereto as changes and alterations may be made without departing from the spirit thereof as defined by the following claims.

Having thus described my invention, what I claim as new and desire to secure by Letters Patent is:

1. In a sawmill set works, the combination of a head block, a set shaft, a rack slidably mounted on said head block and geared to said set shaft, a setting knee slidably mounted on said rack and adjustably connected therewith, a lever for independently adjusting said knee, and a flexible tension connection extending from the set shaft to said lever.

2. In a sawmill set works, the combination of a head block, a set shaft, a rack slid-

- ably mounted on said head block and geared to said set shaft, a setting knee slidably mounted on said rack and adjustably connected therewith, a lever for independently adjusting said knee, a tension lever connected to said adjusting lever, a flexible connection extending from the set shaft to said tension lever, and a tensioning device acting upon said connection.
- 10 3. In a sawmill set works, the combination of a head block, a set shaft, a rack slidably mounted on said head block and geared to said set shaft, a setting knee slidably mounted on said rack and adjustably connected therewith, a lever for independently adjusting said knee, a connection extending from said set shaft to said lever, and a tension cylinder provided with a piston member having a sheave over which said 20 connection passes.
4. In a sawmill set works, the combination of a head block, a set shaft, a rack slidably mounted on said head block and geared to said set shaft, a setting knee slidably mounted on said rack and adjustably connected therewith, a lever for independently adjusting said knee, a connection extending from said set shaft to said lever, a tension cylinder provided with a piston member 25 having a sheave over which said connection passes, and a tension spring within said cylinder for projecting said sheave.
5. In a sawmill set works, the combination of a head block, a set shaft, a rack slidably mounted on said head block and geared to said set shaft, a setting knee slidably mounted on said rack and adjustably connected therewith, a lever for independently adjusting said knee, a flexible connection 30 between said set shaft and lever, a tension device comprising a cylinder provided with a piston member carrying at one end a sheave over which the connection passes and at its opposite end a threaded shank, a head for said cylinder, a spring disposed between said head and piston member, and an adjustable nut mounted upon said shank to engage said head when establishing the tension of said spring action.
- 40 6. In a sawmill set works, the combination of a head block, a set shaft, a rack slidably mounted on said head block and geared to said set shaft, a setting knee slidably mounted on said rack and adjustably connected therewith, a lever for independently adjusting said knee, a flexible connection from said shaft to said lever, a tension device over which said connection travels, and means for adjusting the tension of said 45 device and limiting its expansive action.
7. In a sawmill set works, the combination with a head block, a set shaft provided with a winding drum, a rack slidably mounted on said head block and geared to said set shaft, a setting knee slidably mounted on said rack, a lever pivoted upon the knee for effecting an independent adjustment thereof, a flexible connection extending from the drum upon the set shaft and adjustably connected to said lever, and a tension device for constantly compensating for slack in said connection.
- 15 8. In a sawmill set works, the combination of a head block, a set shaft, a setting knee, a looped connection between said set shaft and knee, and tension means acting upon the loop of said connection to maintain a constant tension and avoid slack therein.
9. In a sawmill set works, a knee mounted upon the head block for rack and pinion adjustment thereon from a set shaft, an individual adjusting lever pivoted upon the knee and connected to said rack, means for holding said lever at its adjusted positions, a flexible connection extending from the set shaft to said lever for adjustable connection thereto, and a tension device carried by the head block and disposed to engage said connection intermediate the set shaft and adjusting lever.
- 20 10. In a sawmill set works, the combination of a head block, a set shaft, a setting knee adjustably connected therewith, means for independently adjusting said knee, and means for maintaining a constant tension between the set shaft and said independent adjusting means.
11. In a sawmill set works, the combination of a head block, a set shaft, a rack slidably mounted on said head block and geared to said set shaft, a setting knee slidably mounted on said rack and adjustably connected thereto, a lever pivotally mounted on the knee for adjusting the same relative to said rack, a tension lever pivoted upon the axis of the adjusting lever and connected thereto at its upper end, a holding sector supported by said knee, a cuff adjustably mounted upon the adjusting lever, and a latch extending through said cuff.
- 25 12. In a sawmill set works, the combination of a head block, a set shaft, a rack slidably mounted on said head block and geared to said set shaft, a setting knee slidably mounted on said rack and adjustably connected thereto, a lever pivotally mounted on the knee for adjusting the same relative to said rack, a tension lever pivoted upon the axis of the adjusting lever and connected thereto at its upper end, a holding sector supported by said knee, a cuff adjustably mounted upon the adjusting lever, a latch extending through said cuff, a block carried by said cuff, and a set screw mounted in said block to engage the adjusting lever and draw said latch into contact therewith.
- 30 In testimony whereof I affix my signature.

HUGO F. BIEDERMANN.
